PULLMAN DAVENPORT AND UPHOLSTERED FURNITURE COMPANY, OF CHI-
CAGO, ILLINOIS, A CORPORATION OF ILLINOIS.

TRANSFER TRUCK.

Application filed February 1, 1922. Serial No. 533,253.

To all whom it may concern:

Be it known that we, JULIUS KRAMER and PERCY J. GREAVES, citizens of the United States of America, and residents of Chicago, 5 county of Cook, and State of Illinois, have invented a new and useful Improvement in Transfer Trucks, of which the following is a specification.

This invention relates to transfer trucks, 10 and especially to devices of this character adapted for handling lumber, as in and about dry-kilns, and such as may be used to advantage also in brick-yards. The main objects of this invention are to provide a 15 transfer truck of the character stated adapted for complete manual control and operation by an attendant stationed thereon; to provide in such a truck a common drive member to receive manual power for operating either the winding drum for loading and unloading the truck, or the traction 20 wheels for moving the truck itself; to provide an improved form and arrangement of drum and traction wheel driving members 25 and gear controlling means therefor; and to provide an improved form of reversible ratchet mechanism for transmitting manual power to the common power shaft.

An illustrative embodiment of this invention is shown in the accompanying drawings, in which—

Figure 1 is a plan of the transfer car and adjacent runway and side tracks.

Figure 2 is partly a side elevation and 35 partly a vertical section on the line 2—2 of Fig. 1.

Figure 3 is a sectional view on the line 3—3 of Fig. 1, showing an enlargement of the gear controlling hand lever and setting 40 mechanism therefor.

Figure 4 is a section on the line 4—4 of Fig. 1 and shows the reversible ratchet lever mechanism for applying hand power to the driving shaft.

Figure 5 is a section on the line 5—5 of Fig. 3.

In the construction shown in the drawings, the transfer car 1 is arranged to travel lengthwise in a runway 2 provided with 50 rails 3, and is adapted to receive loaded lumber bunks 4 or the like from the three-rail

side tracks 5, disposed at right angles to the runway 2 preferably on both sides thereof.

Said truck 1 comprises mainly a frame including longitudinal side beams 6, a series of 55 cross beams 7 braced by plates 7', a platform 8 at one end whereon the operator may stand, load receiving rails 5' and certain operating mechanisms to be described.

Said truck is provided with four supporting wheels 9 arranged in coaxial pairs, one pair being disposed inward some distance from the platform end and secured on a common driving shaft 10 to which at least one of said wheels is fixed. Said shaft is 60 provided with a winding drum 11 mounted turnably and slidably thereon, and certain gear mechanism to be described.

On the platform end of said truck, and positioned lengthwise of the truck, is mounted 70 a common driving shaft 12, and means for rotatively operating same manually, said means including a hand lever 13 and ratchet mechanism which will also be described.

Gear controlling means are also provided 75 on platform 8 whereby the power from shaft 12 may be applied either to the traction wheels or to drum 11, said means including a horizontal lever 14 extending from shaft 10 to platform 8 and an upright hand lever 80 15 having means 16 for setting the same adjustably.

Referring to Figure 4 the hand power lever 13 is provided with a snap-over reversible ratchet mechanism 17 arranged to, 85 coact with a ratchet wheel 18 fixed on the adjacent end of shaft 12. The lever 13 is pivoted on shaft 12, and the mechanism 17 includes a double-ended pawl 19 pivoted at 20 to lever 13, in combination with an inverted T-member 21 pivoted at 22 to lever 13 at a point above pivot 20. The ends of detent 19 and the parallel arms of member 21 are connected by a pair of parallel links 23. A tension spring 24 is connected at its 90 lower end as at 25 to lever 13, between pivots 20 and 22, and its upper end is secured to a medial point 26 on the upright handle part 27 of member 21. As viewed in Figure 4 from the platform side, the ratchet is set 100 for turning the wheel 18 and shaft 12 counter-clockwise. In order to reverse the direc-

tion, the handle part 27 is swung to the right. This reverses the tilt of pawl 19 as will be understood.

Referring to Fig. 1, the opposite end of shaft 12 from lever 13 is provided with a bevel pinion 28 fixed thereon. The drum 11 is provided on its end adjacent to shaft 12 with a bevel gear 29 secured co-turnably thereto, and shaft 10 is provided with a bevel gear 30 on the opposite side of shaft 12. The drum 11 and gear 30 are slideable lengthwise on shaft 10, gear 30 being splined to and being co-rotatable with said shaft, whereas drum 11 though mounted upon is rotatable independently of shaft 10. A spacer or filler block in the form of a sleeve 31 is provided on shaft 10 between gears 29 and 30 to hold them spaced apart sufficiently to provide for limited play of said gears relative to gear 28.

In order that gears 30 and 29 may be alternately engaged with gear 28, at the will of the operator, gear 30 is provided with a hub 32 and with a collar 33 mounted in a groove 32' thereon, and drum 11 is provided with a hub 34 having a collar 35 thereon fitting in the groove 34', and said collars are connected operatively to the gear control lever 14 as will now be described.

Secured to the truck frame are two fulcrum arms 36 and 37 adjacent to the ends of the shaft 10 respectively. Lever 14 is pivoted at 37' to fulcrum 37 and its forked short arm is pivoted at 39 to the collar 35. A short lever 40 parallel with lever 14 is pivoted at 41 to fulcrum 36. One end of said lever 40 is bifurcated and pivoted at 42 to collar 33, and its other end is pivoted at 40' to one end of a link 43. The other end of said link 43 is pivoted at 43' to lever 14 on the opposite side of pivot 37 from the collar 35. This mechanism is so proportioned that movement of lever 14 produces a corresponding movement of drum 11 and gear 30 lengthwise of shaft 10 whereby the driving gear 38 is engaged to either gear 29 or gear 30 depending on the position of the gear controlling handle 15 and lever 14.

Referring to Figs. 3 and 5, the lever 15 is pivoted at 44 to a bracket 45 fixed on the truck frame. The lower end of lever 15 is rounded as shown at 46 and extends in loose fitting relation through an aperture 47 in the outer end of lever 14, which for this purpose may be bifurcated as shown in Fig. 5. A guide plate 48 is secured to the under side of the end bar 7 of the truck frame and provides a slot 49 to receive said lever 14. In order to enable the operator to set lever 14 in any desired position, the lever 15 is provided with a spring urged hand actuated detent 50 to engage the toothed segment 51 on the support 52 which also bears the bracket 15.

Referring now to the winding drum 11 65 and the means for drawing loaded trucks or lumber-bunks 4 onto and off from the transfer truck, the cable 52 has one end secured to the drum and extends lengthwise of the truck 1 and thence around the sheave 53 70 which is mounted to slide freely in its axial direction on the supporting pivot shaft 54 parallel with shaft 10. From said sheave 53 the cable extends around the sheave 55 of pulley block 55' and thence laterally either 75 to or past a sheave 56 mounted for free axial movement on a pivot shaft 57 disposed parallel with the side bars 6 of the main frame.

In order that loads may be handled relative to the side tracks 5 on either side of truck 1, the pulley block 55' is carried by a link 58 which is pivoted at 59 to the bracket 60 on the adjacent frame bar 7. Said link 58 is provided with a swivel joint at 61 so as to readily accommodate the necessary over-turning movement of the sheave 55 in reversing the cable to operate from one side of the truck to the other as suggested by the dotted lines on Figure 1.

The operation of the truck is as follows: 90 First, in order to propel the truck 1 along the rails 3 the hand lever 15 is swung to the right as viewed in Figure 3. This throws the long arm of lever 14 toward shaft 12 and thereby engages gear 30 with gear 28. Gear 28 being fixed on the shaft 12, and gear 30 being splined to the shaft 10 on which the corresponding traction wheels 9 are keyed, rotation of shaft 12 in one direction or the other causes corresponding movement of the truck 100 on the rails 3. Rotation of shaft 12 is effected by the operator grasping the handle 13 while standing on platform 8 and swinging said handle back and forth, whereby power is transmitted from said handle 105 through the ratchet mechanism to shaft 12. The movement of the car is reversed by reversing the position of handle 27 which controls the detent 19.

Second, in case the drum 11 is to be operated for loading or unloading the truck the lever 15 is reversed, thereby swinging the long end of lever 14 away from shaft 12. This throws the drum 11 and gear 29 into engagement with gear 28 and at the same time 115 throws gear 30 out of engagement. In order to apply power to the drum for winding up the cable the ratchet handle 27 is thrown to the left as shown in Figure 4. Then when the hook 62 on the end of cable 52 is attached to a load the latter will be drawn upon the car as will be understood by reference to the arrangement shown in Figure 1. In case the load is to be withdrawn from the car and delivered, for instance, to the side tracks at the far side of the truck, the cable 52 will extend around the remote sheave 56 and thence back to the near side of the

lumber-bunk or other load-carrying truck, whereupon application of power will draw the same off from truck 1.

Third, in case the cable is to be unwound 5 the handle 15 is thrown to transfer engagement of gear 28 from gear 29 to gear 30, or gear 28 may be left in its neutral half-way position. Then the cable may be unwound by grasping the cable 52 or the hook 62 and 10 pulling thereon, as will be apparent.

With the truck above described one man working alone may readily and safely perform the loading and unloading operations and the propelling of the truck, such as 15 would require a gang of men if manual force were applied directly, and such as would often prove hazardous to the workmen.

Although but one specific embodiment of 20 this invention has been herein shown and described, it will be understood that numerous details of the construction shown may be altered or omitted without departing from the spirit of this invention as defined by the following claims.

25 We claim:

1. A transfer truck comprising in combination a frame having supporting wheels, manually operated power means, a winding drum and cable therefor arranged for drawing loads onto and off from the truck, and 30 manually operated gear controlling means to connect said power means either to said drum or to one or more of said wheels.

2. A transfer truck comprising in combination a frame having supporting wheels, 35 load receiving rails, an operator's platform, manually operated power means, a winding drum and cable therefor arranged for drawing loads onto and off from said rails and 40 manually operated means for connecting said power means either to said drum or to one or more of said wheels.

3. A transfer truck comprising in combination a frame having supporting wheels, 45 a load receiving part, an operator's platform, gearing, manually operated power means, a winding drum and cable therefor arranged for drawing loads onto and off from the truck, and manually operated gear controlling means for connecting said power means either to said drum or to one or more of said wheels, said gear controlling means including a lever connected to said drum and to a gear which is operatively connected 50 to one of said wheels.

4. A transfer truck comprising in combination a frame having supporting wheels, manually operated power means, a winding drum and cable therefor arranged for drawing 55 loads onto and off from the truck, power transmitting gearing, and manually operated gear controlling means for connecting said power means either to said drum or to one or more of said wheels, said gear controlling means including a handle, a pair 60

of levers operatively connected to said handle and also connected to said drum and to a gear included in said gearing which is operatively connected to one of said wheels.

5. A transfer truck having a plurality of 70 supporting wheels and a driving shaft operatively connected to and coaxial with one of said wheels, in combination with a bevel gear splined to said shaft and a winding drum with a bevel gear fixed thereon also 75 carried on said shaft, means for shifting said drum and gears longitudinally of said shaft, a driving bevel gear having a substantially fixed axis and disposed between said gears whereby power may be transmitted to either of the two first mentioned 80 gears and means for throwing either of the two first mentioned gears into engagement with the third mentioned gear.

6. A transfer truck having a plurality of 85 supporting wheels and a driving shaft operatively connected to and coaxial with one of said wheels in combination with a bevel gear splined to said shaft and a winding drum with a bevel gear fixed thereon also 90 carried on said shaft in free turning relation thereto, means for shifting said drum and gears longitudinally of said shaft, a driving gear having a substantially fixed axis and disposed between said gears whereby power may be transmitted to either of said 95 bevel gears and means for throwing either of said bevel gears into engagement with the third mentioned gear.

7. A transfer truck having a plurality of 100 supporting wheels and means for applying power to one or more of said wheels, said means including a shaft, mechanically operative connections extending from said shaft to said one wheel, a ratchet device adapted 105 for hand operation connected to said shaft, said connections including a pair of bevel gears, and means for disconnecting said gears.

8. A transfer truck having rails thereon 110 to support a load, a winding drum disposed parallel with said rails, means for applying power to said drum, a cable for said drum, and a plurality of sheaves arranged 115 to carry a part of said cable in a position parallel with said rails, one of said pulleys being provided with a swivel block and said block being pivotally supported to swing to accommodate disposition of the load receiving end of the cable in either direction. 120

9. A transfer truck having rails thereon to support a load, a winding drum disposed parallel with said rails, manual means for applying power to said drum, a cable for said drum, and a plurality of sheaves arranged 125 to carry a part of said cable in a position parallel with said rails, whereby said truck may be loaded and unloaded manually.

10. A transfer truck having rails thereon 130

to support a load, a winding drum disposed parallel with said rails, manual means for applying power to said drum, a cable for said drum, and a plurality of sheaves arranged to carry a part of said cable in a position parallel with said rails, one of said sheaves being slidale in its axial direction and another of said pulleys being provided

with a swivel block, said block being pivotally supported to swing horizontally to accommodate disposition of the load receiving end of the cable in either direction.

Signed at Chicago this 26 day of Jan. 1922.

JULIUS KRAMER.
PERCY J. GREAVES.
